2 SHEETS—SHEET 2.

UNITED STATES PATENT OFFICE

JOHN L. HALL, OF SCHENECTADY, NEW YORK, ASSIGNOR TO GENERAL ELECTRIC COMPANY, A CORPORATION OF NEW YORK.

SEARCH-LIGHT MECHANISM.

1,105,771.

Specification of Letters Patent.

Patented Aug. 4, 1914.

Application filed April 21, 1910. Serial No. 556,685.

To all whom it may concern:

Be it known that I, JOHN L. HALL, a citizen of the United States, residing at Schenectady, county of Schenectady, State of New York, have invented certain new and useful Improvements in Search-Light Mechanism, of which the following is a specification.

This invention relates to searchlight projectors or the like and has for its object the provision of a device of this character which is simple and efficient in construction and which provides convenient means for adjusting and manipulating the parts.

One of the objects of my invention is to provide means for conveniently adjusting the electrodes with reference to each other. In accomplishing this, I provide means whereby one of the electrodes may be adjusted with reference to the other in two planes. This may be done from a position outside of the projector casing.

Another object of my invention is to provide means whereby the lamp mechanism may be quickly replaced. This is accomplished by so arranging the parts that the lamp mechanism may be removed as a unit from the casing. The arrangement is such that the lamp mechanism is movably mounted upon an adjustable carriage, so that in ordinary adjustment the carriage is moved while the lamp mechanism may be removed and replaced without disturbing the adjustment. I also provide means whereby the current to the lamp is automatically cut off when the lamp is removed.

Another object of my invention is to provide means whereby the adjusting rods which extend through the casing may automatically detach themselves from the lamp mechanism when the latter is removed and may be again easily attached to the mechanism when the lamp is replaced.

Other objects of my invention will appear in the course of the following specification, in which I have shown my invention embodied in concrete form for the purposes of illustration.

In the drawings disclosing my invention embodied in concrete form, Figure 1 repre-

sents a sectional view of the lower part of the projector; Fig. 2 shows a similar view with the lamp mechanism moved upon the carriage so as to open the circuit; Fig. 3 represents a plan view of the lamp mechanism and the carriage; Figs. 4, 5 and 6 show the details of construction of the electrode adjusting mechanism; and Fig. 7 is a reduced view of the whole projector showing the position of the adjusting rods in the casing.

Referring to the drawings, 10 represents the casing of the projector, within which is mounted the carriage 11. This carriage is movably mounted in guides 12 and is adjusted by means of hand wheel 13 13', which operates a spur gear 14 through worm gearing 15. This spur gear cooperates with a rack 16 upon the carriage to move it forward and back, for focusing the lamp. The lamp mechanism as a unit is slidably mounted in the guides 12.

The particular form or structure of the lamp mechanism forms no part of my invention. For purposes of illustration, I have shown the lamp mechanism which is described in my previous application, Serial No. 422,253. It is therefore unnecessary to describe the details of this lamp mechanism. Generally speaking, the lamp consists of two upright frames 18 and 19, each mounted upon rollers in the guides 20. These frames are inclined away from each other so that the tops are a sufficient distance apart to admit the two electrodes. The frames are moved in the guides 20 toward and from each other by electromagnetic mechanism, described in previous application above referred to. The lamp mechanism slides in the guides 12 and is forced inward until the switch blades 23 on the lamp frame engage the clips 24 on the carriage provided with a flexible connection 24' to close the circuit through the lamp. In order to secure the lamp and carriage together, with the circuit closed, I provide a screw 25 on shaft 25' having a knurled head 26, screwed into the lug 27 in the carriage. By turning the head 26 the lamp will be released from the carriage and may be pulled out of the casing.

This is sometimes desirable where a quick renewal of the carbons is required. The lamp as a whole may be removed, and another inserted in its place. The lamp always goes back to the exact place in the casing which is left and the adjustment is therefore not disturbed.

Referring now to Figs. 4, 5, and 6, it will be seen that the electrode 21 is pivoted for movement in two planes and that means are provided for adjusting the electrode in the two planes in an accurate and simple manner from a point outside of the projector casing. Electrode 21 is mounted in a holder or support 28, having secured to it a shaft 29 forming a journal for the holder. The upper end of the frame 18 is provided with lugs 30 forming bearings for shaft 31. This shaft is provided with a spiral thread or rib 32 adapted to engage a pin or projection 33 in the holder 28. The bearing bracket 34 having ears 35 mounted upon the shaft 31 provides a bearing for the shaft 29. The shaft 29 extends through the bearing 34 and the holder is supported in the bearing at 36. By turning the shaft 31, the projection 33 will be engaged by the rib 32 and the electrode thereby moved in a horizontal plane in the bearing 34. A second shaft 37 is mounted in the frame 18 and is also provided with a spiral rib. In this case I provide a disk having a spiral 38 extending transversely of the shaft instead of longitudinally, as in the case of the spiral 32. A pin 39 projecting from the bearing 34 engages the spiral 38 so that when the shaft 37 is turned, the bearing will be moved about the shaft 31 as a center. This will cause the electrode to move in a vertical plane. Secured to each of the shafts 31 and 37 is a universal coupling 40 which in turn is connected with sleeves 41 by insulated couplings 42. The sleeves 41 are adapted to receive the shafts 43 and a pin 44 fits into a slot in the sleeve, as shown in Fig. 3. The shaft 43 is arranged to slide through a ball bearing in the projector casing. The ball 45 is provided with an opening to receive the shaft and is held in place by plate 46. By removing the plate, the ball with the shaft therein is readily removed. A lever 47 pivoted in a slot in the shaft 43 is notched at its inner end at 48 to engage the inside of the ball, while the outer end is sprung so as to force the notch upward into engagement with the bearing. The hand wheel 49 mounted upon each of the shafts is of such a character that the finger of the operator may easily engage the lever 47. By pressing the lever, the shaft may be slid out of the sleeve 41 and as the shaft is moved inward, it is automatically locked by the notched lever. By this arrangement it will be seen that when the lamp is with-

drawn from the casing, the operating shafts 43 automatically free themselves from the lamp by turning in their ball bearings to the position shown in Fig. 3. When the lamp is replaced, the shafts are again connected with the lamp by simply inserting the shafts 43 into the sleeves 41. It will be seen, therefore, that by turning one of the hand wheels 49, the electrode 21 will be moved in a horizontal plane with reference to the electrode 23', whereas by moving the other wheel, the electrode may be moved in a vertical plane, and that the adjusting mechanism in no way hampers the removal and replacing of the lamp.

The lamp may be focused with great precision and when it is removed and replaced, or even when a new one is inserted in its stead, its focal adjustment will not be altered. It will be seen that as the lamp is removed the current is automatically cut off and the operator may then handle the lamp without danger of shock.

It is obvious, of course, that while I have shown my invention in connection with arc lamps for searchlight projectors, that it is not necessarily limited in its application to this particular form of device. Furthermore, I do not regard my invention as limited to the particular arrangement or construction of parts herein shown and described, since various modifications thereof will suggest themselves to those skilled in the art without departing from the spirit of my invention, the scope of which is set forth in the annexed claims.

What I claim as new and desire to secure by Letters Patent of the United States, is:

1. In a searchlight projector or the like, the combination with an electrode support having pivotal mountings at right angles with each other, a pair of adjusting spirals rotatably mounted on parallel axes, and pins engaging the spirals and moved thereby to turn the support on its pivots.
2. In a searchlight projector or the like, the combination with a shaft having a spiral rib extending longitudinally thereof, an electrode holder having a projection engaging said rib, a second shaft parallel with said first shaft having a spiral rib extending transversely of its axis, and a pivoted bearing for rotatably supporting the holder and having a projection engaging said latter rib.
3. In a searchlight projector or the like, the combination with a fixed frame, parallel shafts rotatably mounted therein having spiral ribs extending longitudinally and transversely thereof respectively, a pivoted bearing bracket having a projection engaging one of said ribs, and an electrode holder having a bearing in said bracket and provided with a projection engaging the other of said ribs.

4. In a searchlight projector or the like, the combination with arc lamp mechanism slidably mounted within the projector casing, of electrode adjusting mechanism having telescoping sectional shafts, one section being connected to the adjusting mechanism by a universal joint, while the other section is slidably mounted in a universal bearing

in the casing and means for locking the latter section in the casing. ¹⁰

In witness whereof, I have hereunto set my hand this 18th day of April, 1910.

JOHN L. HALL.
